(57) CLAIM

The ornamental design for a cosmetic product package, as shown and described.

DESCRIPTION

FIG. 1 is a front perspective view of a cosmetic product package embodying the present design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The dashed lines are provided for the purposes of illustrating parts related to the cosmetic product package that form no part of the claimed design.

The figures include surface shading lines that merely clarify contours of various surfaces and does not indicate surface texture, material, or color.
